US00D928200S

(12) **United States Design Patent** (10) Patent No.: **US D928,200 S**
Connor et al. (45) Date of Patent: **** Aug. 17, 2021**

(54) **DISPLAY SCREEN OR PORTION THEREOF WITH ICON**

(71) Applicant: **Apple Inc.**, Cupertino, CA (US)

(72) Inventors: **Teofila Connor**, San Francisco, CA (US); **Christopher Wilson**, San Francisco, CA (US)

(73) Assignee: **Apple Inc.**, Cupertino, CA (US)

(**) Term: **15 Years**

(21) Appl. No.: **29/737,008**

(22) Filed: **Jun. 4, 2020**

Related U.S. Application Data

(63) Continuation of application No. 29/682,307, filed on Mar. 4, 2019, now Pat. No. Des. 886,844, which is a continuation of application No. 29/606,386, filed on Jun. 4, 2017, now Pat. No. Des. 842,333.

CLAIM

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon showing the claimed design; and,

FIG. 2 is another embodiment thereof.

The broken lines in the figures show a display screen or portion thereof, and form no part of the claimed design.

1 Claim, 1 Drawing Sheet
(1 of 1 Drawing Sheet(s) Filed in Color)
